CONTROL FOR AN ELECTRIC BLANKET

Robert O. Ernest, Oak Park, Ill., assignor to Sunbeam
Corporation, Chicago, Ill., a corporation of Illinois

Filed Apr. 2, 1963, Ser. No. 74,270

Term of patent 14 years

(Cl. D26—13)

Fig. 1.

Fig. 2.

Fig. 6.

Fig. 3.

Fig. 4.

Fig. 7.

Fig. 5.

FIG. 1 is a front perspective view of a control for an electric blanket showing my new design;

FIG. 2 is a side elevational view thereof;

FIG. 3 is a rear elevational view thereof;

FIG. 4 is a top plan view thereof;

FIG. 5 is a bottom plan view thereof;

FIG. 6 is an enlarged fragmentary sectional view taken along line 6—6 in FIG. 2; and

FIG. 7 is a sectional view taken along line 7—7 in FIG. 4.

I claim:

The ornamental design for a control for an electric blanket, as shown.
